UPRIGHT PIANO

Robert Percy Brasted, Finsbury Park, London, England, assignor to W. G. Eavestaff & Sons Limited, Finsbury Park, London, England, a company of Great Britain

Application December 6, 1939, Serial No. 307,888
In Great Britain December 17, 1938

1 Claim. (Cl. 84—240)

This invention relates to improvements in upright pianos and it has for object to provide a piano having a case which requires a smaller amount of material than cases as at present constructed and also by which other advantages may be obtained.

In a miniature upright piano the action is wholly or mainly below the keyboard. The ends of the case extend a little above the keyboard. 10 The piano is closed at the top by the fall-back and the fall which are substantially level with the tops of the ends. The fall-back extends over the top of the frame so that the height of the ends is the same as or substantially the same 15 as that of the frame. In such a construction the keyboard is then higher than it need be for convenience which necessitates the use of a relatively high music stool.

In an ordinary upright piano the ends extend 20 up to the top of the frame and forward of it, the fall-back and fall extending from the front panel which closes the front of the case above the keyboard.

In another construction of upright piano, the 25 case ends are widened so that the keyboard is located wholly within the case ends, and a top panel or door is arranged, when the piano is not in use, above and in front of the keyboard to close the front of the case. The door is supported 30 on the front ends of links whose rear ends are pivoted to the case ends, so that it can be swung back bodily to a position at the rear of the keyboard when the piano is in use. The front portion of the case top, which is flush with the tops 35 of the case ends and extends rearwards over the top of the frame, hinges back to allow the door to make this rearward movement, throughout which it is held substantially vertical.

It is an object of the present invention to provide 40 a construction of piano case in which the ends are shorter than normally whereby a saving of material is effected in making the piano case. At the same time the keyboard is lowered to a more convenient position and the top of the 45 frame is readily accessible for adjustment of the wrest pins for tuning, or for other purposes. The ends of the case may still extend forward to the front edge of the keyboard and the latter may be covered by a panel or door. The invention 50 also offers the advantage that the top of the case may be shaped to the contour of the top of the frame, thereby providing a very attractive finish to the upper part of the piano.

In order to enable the invention to be readily 55 understood, reference is directed to the accom-

panying drawings which illustrate several forms thereof by way of example and wherein:

Figure 1 is a perspective view of the upper part of an upright miniature piano constructed in accordance with the present improvements. 5

Figure 2 is a part-sectional end elevation of the same piano, the section being central.

Figure 3 is a perspective view of another construction of miniature upright piano in accordance with the invention, the removable housing 10 for the upper part of the frame being shown in raised position, and

Figure 4 is a similar view illustrating a further construction of miniature upright piano in accordance with this invention. 15

In Figures 1 and 2, the ends *a* of the piano case terminate short of the top of the frame *b* by a distance *c* which may be say four or five inches and represents an advantageous shortening of the length of these ends and consequent 20 saving of material. The keyboard *d* is also lowered the same distance. The fall-back *e* extends rearward to a position a short distance in front of the upper end of the frame *b* and is suitably secured to the ends *a*. The fall *f* is 25 hinged to the fall-back *e* in the usual way at *g* and the name board *h* slopes downwards and forwards from under the hinge *g* to a point over the rear end of the keys in normal fashion. The top part of the frame is enclosed in a removable 30 housing *k* which at its rear edge *l* bears on parts of the wooden framework of the piano, at its ends *m* bears on the ends *a* of the piano case, and at its front edge *n* bears on the rear edge of the fall-back *e*, suitably through a pad *i*. This housing 35 *k* is free and may be easily lifted off when it is desired to remove the fall and fall-back or when it is desired to examine or have access to the top of the frame for any reason, for instance to adjust the wrest pins *o* for tuning 40 purposes.

In some constructions of piano there is no back so that the rear edge *l* of the housing *k* has no bearing on another part.

In Figure 3, the housing *k* is hinged or pivoted 45 at one end *p* to the adjacent end *a* of the piano case, so that it is removable from the upper end of the frame *b* by lifting it about the hinge or pivot. In the position, which is shown in the drawings, the end of the housing remote from 50 the hinge or pivot may be supported by a "prop stick" or strut *r* permitting the said housing to be inclined in the vertical plane in a manner similar to that used in supporting the tops of grand pianos. This is a favourable condition for 55

permitting more readily the escape of sound from the piano when in use.

According to the construction shown in Figure 4, the removable housing *k* is adapted to be secured in position by providing it at the ends with metal pins *s* which fit in metal bushed holes or sockets *t* in the tops of the ends *a* of the piano case. Other means than pins and sockets and known in the art may be employed for securing the removable housing *k* in position.

In each illustrated construction, the housing *k* is readily removable from the upper end of the frame *b*. The drawings also show that where the said frame is curved in shape at its top edge, 15 the housing *k* may be similarly shaped. This not only saves material but gives a pleasing appearance to the finished piano.

In applying the invention to an ordinary upright piano, the ends of the case again would be 20 terminated short of the top of the frame in a similar manner to that already illustrated and the top of the frame would also be enclosed in a similar removable housing, resting at the back on the wooden framework of the piano, at the 25 front on the back edge of the top which would extend rearwards to a position a short distance

in front of the upper end of the frame, and at the sides on the tops of the ends of the piano case, as will be understood without further illustration. Obviously, similar construction is also applicable to an upright piano of the kind described above 5 in which the case ends are widened to receive the keyboard between them, and a front door or panel is movable bodily to open and close the piano case, the hinged front half-top of the case in raised position suitably resting against 10 the removable housing enclosing the top of the frame.

What I claim is:

An upright piano having a vertical frame with 15 wrest pins at the top thereof, a case enclosing said frame including ends extending upwardly from the bottom of the piano frame, said ends terminating short of the top of the frame at substantially the level of the wrest pins to enclose the greater part of the frame, and a unitary 20 housing removably mounted on the case and on said ends and entirely enclosing the otherwise exposed upper portion of the frame, said housing having a contour similar to that of the upper portion of the frame.

ROBERT PERCY BRASTED.
